UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed December 20, 1924. Serial No. 757,158.

This invention aims to provide an improved separable fastener.

In the drawings, which illustrate a preferred and a modified form of my invention:—

Fig. 1 is a front elevation of the preferred form of fastener;

Fig. 2 is a section on the line 2—2 of Fig. 1, being partly in elevation;

Fig. 3 is a section similar to Fig. 2, but showing the stud and locking means in normal position and the socket in the position prior to contraction of the head of the stud;

Fig. 4 shows a further step in forcing the socket over the head of the stud, the stud having been contracted and the locking part having been forced into unlocked position by the contraction of the stud;

Fig. 5 is a front elevation of a modified form of fastener; and

Fig. 6 is a side elevation of the fastener shown in Fig. 5.

Referring to the Figures 1 through 4 and to the preferred form of my invention, I have shown a socket of the usual grommet type including a front plate 1 and clench plate 2 secured to a curtain 3 presenting a stud-receiving aperture 4 for receiving the head of a contractile and expansible stud, as illustrated in Fig. 2.

The stud is pressed from a single sheet of metal and presents a head 5, a neck 6, a shank 7, a base 8, and a plurality of longitudinal slits 9 extending from the head 5 to the base 8 and secured to the body 10 of an automobile, or the like, by the usual attaching screw 11 having a hexagonal head 12 secured to the base 8 of the stud. Thus I have provided a stud which is contractile when engaging the grommet and expansible when engaged therewith.

While the socket may be held on the stud by the resiliency of the stud itself, I prefer to provide locking means to prevent contraction of the stud when the socket is secured thereto, thus providing a lock against accidental separation of the socket from the stud by wind or other strain on the curtain 1.

A preferred form of locking means comprises a single sheet of metal pressed out to form a press-button 13 entered in the stud and having a portion thereof protruding through an aperture 14 in the end of the stud, a relatively steep cam shoulder 15 adjacent and engaged with the outer end of

the head of the stud and a locking surface 16 normally spaced slightly away from the interior surface of the neck 6 of the stud, the whole being normally urged forward by a spring 17.

In securing the socket to the stud, the head of the stud passes through the stud-receiving aperture 4 and the peripheral wall surrounding the aperture contacts with the sloping part of the head of the stud, as best illustrated in Fig. 3, and as the socket is forced toward the neck (Fig. 4), the head contracts and those portions 18 of the head of the stud that surround the aperture 14 engage the cam shoulder 15 of the press button and force the locking means against the pressure of the spring 17, away from the interior surface of the neck of the stud, thereby to permit contraction of the stud and engagement of the socket with the neck 75 of the stud. When the socket passes to the neck of the stud, the parts expand until the exterior surface of the neck engages the peripheral wall of the stud-receiving aperture 4, which is slightly less in diameter than 80 the normal diameter of the neck. Thus the stud is maintained in a slightly contracted condition, so that the spring 17 may force the locking means toward its normal position and engage the locking surface 16 with 85 the interior surface of the neck of the stud, thereby preventing contraction of the stud. When the parts are in the positions shown in Fig. 2, the socket cannot be separated from the stud by strain exerted on the curtain, because an upward or outward pull on 90 the socket tends to crowd the socket over the head of the stud and as the pressure, so exerted upon the stud, is so remote from the cam shoulder-engaging portions 18 that it is not sufficient to displace the locking means.

The tendency, therefore, is to increase the grip between the interior surface of the neck of the stud and the locking surface 16 of the locking means, thereby preventing further contraction of the stud and separation of the socket therefrom.

Separation of the socket from the stud may be effected very conveniently by grasping the lower edge of the curtain and exerting an outward pull thereon, at the same time pressing the press button with the thumb, thereby to disengage the locking surface 16 from the neck of the stud and permit contraction of the head of the stud. 110

2

Referring now to the modified form of my invention, as illustrated in Fig. 5 and 6, I have shown a socket substantially the same as shown in the preferred form of my invention, except that in this instance the stud-receiving aperture 19 is slightly elliptical. The stud in this instance is exactly the same as in the preferred form except that resiliency is provided by two longitudinal slots 20, 20 instead of four, as illustrated in the preferred form. Thus this construction of stud requires an elliptical stud-receiving aperture in the socket because the head of the stud contracts only in one direction and not equally in all directions. The rest of the parts and the operations thereof are the same as described relative to the preferred form of my invention.

While I have shown and described a preferred form of my invention, it will be understood that my invention is best defined in the appended claims.

I claim—

1. In a stud and socket fastener, a socket 25 presenting a stud-receiving aperture surrounded by a wall of fixed dimensions, a cooperating stud having a contractile and expansible head for passage through said aperture, locking means carried by said stud 30 and normally preventing substantial contraction of said stud and means operable by passage of said head through said aperture to force said locking means out of locking position relative to said stud, thereby to permit engagement of the stud and socket.
2. In a stud and socket fastener, a socket 35 presenting a stud-receiving aperture surrounded by a wall of fixed dimensions, a cooperating stud having a contractile and expansible head for passage through said aperture, locking means carried by said stud 40 and normally preventing substantial contraction of said stud, means cooperating between said head and said wall when passing said head through said aperture to force said locking means out of locking position relative to said stud, thereby to permit engagement of the stud and socket, and a press- 45 button manually operable to displace said locking means thereby permitting contrac- 50

tion of said head and disengagement of the socket and the stud.

3. In a stud and socket fastener, a socket presenting a stud-receiving aperture surrounded by a wall of fixed dimensions, a 55 cooperating stud having a contractile and expansible head for passage through said aperture, a neck for engagement with the wall surrounding said stud-receiving aperture, a shiftable member assembled within 60 and carried by said stud and presenting a locking portion adjacent the neck of the stud normally permitting initial contraction of the head when passing through said aperture, while preventing contraction of said 65 head and neck when the stud and socket are engaged, cam means operated by contraction of said head when said head engages said wall to pass through said aperture, thereby automatically to shift said locking portion 70 out of locking engagement with said neck, a spring for moving said shiftable member into its normal position, and a press-button manually operable to move said shiftable member to permit separation of the socket 75 from the stud.

4. In a stud and socket fastener, a stud having a contractile and expansible socket-engaging head, spring-pressed locking means carried by said stud and normally prevent- 80 ing substantial contraction of said head, and means operable by engagement of said head with a socket of fixed dimensions for automatically displacing said locking means against the pressure of a spring, to permit 85 contraction of said head and engagement with said socket.

5. A fastener stud including a contractile and expansible socket-engaging head, lock- 90 ing means carried by said stud and displace- able to permit contraction of said head, and means operable by the contraction of said head when forced into a socket provided with a stud-engaging wall of fixed dimensions for automatically moving said locking 95 means out of locking position.

In testimony whereof, I have signed my name to this specification.

FRED S. CARR.
